REFLECTING ELECTRIC LAMP

Clarence Birdseye, Gloucester, and Clarence K. Reiman, Newton, Mass., assignors to Birdseye Electric Company, Gloucester, Mass., a corporation of Delaware

Application December 19, 1935, Serial No. 55,203

10 Claims. (Cl. 176—34)

This invention concerns improvements in the design of reflecting electric lamps and particularly lamps adapted for indirect or cove lighting, that is, lamps adapted to be placed in a cove or channel near the junction of the wall and ceiling of a room, concealed from the direct view and so designed and placed that their radiation is directed generally toward predetermined portions of the ceiling of said room, whereby the illumination of objects below is obtained by diffuse reflection from the ceiling.

As is well known, indirect or cove lighting, while highly desirable from many viewpoints is in general far less efficient than direct lighting. It is therefore particularly important in this field that the lamps themselves be of the highest possible efficiency in addition to having the other qualifications which may be more directly related to the problem.

When standard lamps are used in indirect lighting installations, and placed horizontally in the cove, adjacent an external reflector, asymmetrical light patterns on the ceiling result from the lack of symmetry of the individual bulbs. Such asymmetrical light patterns are highly objectionable from the decorative and efficiency standpoints. If the bulbs are placed vertically in order to avoid this asymmetry of light pattern, an excessively large reflector and an unduly large cove become necessary, thus entailing considerable expense, and possibly conflicting with the architectural design of the room. The external reflector required, whether the bulbs be placed horizontally or at some other angle, is in addition an inefficient reflector.

It is an object of this invention to provide a lamp which is peculiarly adapted to indirect or cove lighting installations in that it results in a marked improvement in lighting efficiency when so used.

Another object of this invention is to provide a lamp which is peculiarly adapted to indirect or cove lighting installations insofar as it produces a symmetrical light pattern on the ceiling although placed with its axis horizontal.

It is a further object of the invention to provide a lamp peculiarly adapted to indirect or cove lighting installations in the sense that it is a self-contained unit, radiator and reflector comprising a single compact structure, and requiring a cove of minimum space requirements.

The preferred form of lamp in accordance with the invention comprises a bulb having a reflecting coating over one-half or approximately one-half its surface, the coating being bounded by a plane in which lies the axis of the bulb, and the bulb itself being symmetrical not only about its own axis but also, with the exception of the neck portion thereof, about an axis perpendicular to

the axis of the bulb. In addition we provide our preferred bulb with a neck reflector which, contrary to the teachings of the prior art, is not mounted with its axis coincident with the axis of the bulb, but at a considerable angle therewith, so that radiation from the filament which strikes this neck reflector will not only be prevented from being absorbed in the mount but will also be immediately reflected out through the transparent wall of the bulb. This construction thus in two senses, first by eliminating absorption, and second by eliminating multiple reflection, improves efficiency. The neck reflector is so formed and placed that its reflecting surface is a substantial continuation of the symmetrical reflecting surface of the bulb itself. This results in a symmetrical radiation pattern on the ceiling when the bulb is in use.

In another form of the invention, useful where decorative features are not of paramount importance, we employ a bulb of standard outward form, which results in considerable economy. In this case, we prefer to employ a neck reflector, either dished or plane, and carefully mounted at such an angle that light rays from the filament impinging thereon will be immediately reflected outward of the bulb. Elimination of multiple reflection and consequent improvement of efficiency is also assisted in some measure by placing the filament not directly at the center of the bulb as in the common practice, but somewhat offset toward the reflecting side thereof. In the case of a bulb of standard form, which is not symmetrical about an axis perpendicular to that of the bulb, some improvement in the symmetry of the illumination pattern may be achieved by moving the filament slightly in the direction of the neck from its usual position. The amount of this preferred displacement is of the order of one-quarter inch for a standard 300-watt bulb.

When, as in any of the subordinate forms of our invention, the filament is positioned wholly within the reflecting area, and thus below the main axis of the lamp, we have found it desirable to bring the lead-in wires and any other filament supports, insulated if necessary, through the sloping oval reflector at the edge of the reflector, rather than through its center, thus leaving the main part of this reflector a smooth unmarred surface. This can also be accomplished by passing them through small holes near the edge of the reflector or through small slits at the edge of the reflector. A slight increase in efficiency results from this off-set arrangement, and a reduction in the tendency to produce shadows of these wires on the ceiling.

It will be understood that our invention includes two main phases: First, the production of a symmetrical illumination pattern, and, sec-

ond, the improvement in efficiency of illumination. This invention covers means for achieving these results in combination, as in the preferred form, or separately. In case only one of the results is desired, for example, the improved efficiency, the invention again covers various means, as briefly outlined above and as explained in greater detail in connection with the diagrams the generic feature being the elimination 10 as far as possible of successive reflections within the bulb.

These and other features of the invention will be best understood and appreciated from the following description of several preferred embodiments thereof selected for purposes of illustration and shown in the accompanying drawings in which,—

Fig. 1 is a view in vertical cross section, partly in elevation of a lamp in horizontal position having a reflecting coating applied to its lower half, together with a polar intensity diagram of the light emitted thereby.

Fig. 2 is a similar view of a lamp equipped with a neck reflector and the corresponding light 25 diagram.

Fig. 3 is a similar view of a lamp having a modified shape and the corresponding light diagram.

Fig. 4 is a similar view of a lamp having its 30 shape still further modified and a corresponding light diagram, and

Fig. 5 is a similar view of a lamp of the general character shown in Fig. 2 but having as an additional feature an offset filament, together 35 with the corresponding light diagram.

In Fig. 1 is shown a reflecting electric lamp having a bulb of standard shape with a silvered reflecting surface applied to the lower half of the bulb and limited by a horizontal plane passing 40 through the main axis of the lamp. The bulb is formed with the conventional cylindrical neck portion and adjacent conical portion and a spherical or bowl portion and the filament is located substantially at the center of curvature 45 of the bowl portion of the bulb. The silvered coating is applied to the lower half of the conical and bowl portions of the bulb in such a manner as to reflect light from the light source O as indicated in the drawings by the various arrows 50 shown. The incident rays and the reflected rays will coincide over the spherical part of the reflecting surfaces, in the case of a point source of light located at the center of the spherical part of the bulb, although of course the angles of incidence and reflection will not be exactly 90°, and will not exactly coincide, when the light rays are emitted from those parts of the filament not at the center of the spherical part of the bulb.

60 The continuous heavy line starting from the filament center, O, and marked A, B, and C and then returning back to O, represent the polar intensity diagram for such a lamp, assuming spherical emission from a point source at the center of the filament, and with 80% reflection efficiency. The case where the filament is not a point but an ordinary extended filament, would be much like this diagram, except that the edges would not be sharply defined. In order to make 65 comparison simpler, in each of the several drawings where these diagrams are shown, the above assumptions have been uniformly applied.

A straight line drawn from O to any point on this curve, A, B, C is proportional to the light 70 intensity in the direction of the straight line,

The diagram and the representation of the lamp axis as shown are assumed to lie in the plane of the paper on which they are drawn, the line which bounds the silvered surface of the bulb lying in a plane perpendicular to the plane of the paper. Since this bulb, and therefore the reflecting surface, is symmetrical about the axis of the lamp, any polar intensity diagram on any plane through the lamp axis will have this same shape.

It will be noted that the part of the diagram marked C, represents the intensity from the direct light only, since no reflected light is sent in the direction of this part of the curve. This intensity of direct light is equal in all directions 15 and in all planes the polar intensity diagram for this direct light only would be the dotted circle continuing from the point 8 through C to the point 7. The part marked A represents the sum of the intensities of the direct light and of the 20 light reflected from the spherical part of the reflecting surface. The spherical reflecting surface reflects light of uniform intensity from the line O—N to the line O—4, and the polar intensity diagram for this sum would be a circle—25 shown partly dotted—from the point 9, through A to the axis N—N'. However, that part of both the direct light and the reflected light from the spherical part of the reflecting surface, falling between the cut-off line O—2 and the axis N—N' is largely lost in the neck section, as is the direct light between O—1 and the axis N—N'.

The conical part of the reflecting surface reflects light between the limiting rays indicated as O—4 and O—5, and this effect is transferred 30 to the polar diagram between the radii O—4 and O—3, the latter being parallel to the limiting ray O—5. The part, B, of the polar intensity diagram therefore represents the sum of the direct light, the light reflected from the spherical part 40 of the reflecting surface, and the light reflected from the conical part of the reflecting surface.

In Fig. 2 is shown this same lamp of standard shape with a sloping dished oval shaped reflector 20 positioned in the stem, and serving approximately as a continuation of the conical part of the reflecting surface. The polar intensity diagram is derived in the same manner as explained for Fig. 1. The light which would otherwise be lost in the neck of the lamp is here reflected out 45 of the bulb by means of the sloping reflector. The limiting ray, marked 5, in this area, which determines the location of the parallel radius O—3 in the polar intensity diagram, shows the improvement in effective reflection, and may be 50 noted by the cross-hatched area between the part of the curve marked B, and the dotted circle 2—A—8. The cut-off angle, made by the line O—2 and the axis N—N' has here also been improved somewhat, resulting in a further utilization 55 of light.

In Fig. 3 is shown a bulb having a cylindrical neck, and an adjacent conical section, but with the ordinary spherical portion elongated in shape, so that the bulb ends in a blunt tip. At the very 60 tip, such a bulb, and therefore the reflecting surface upon it, would of course be perpendicular to the axis N—N', and the ray striking the reflecting surface at this point would be reflected back to the sloping reflector. However the 70 amount of light involved and so reflected twice is of little practical importance, and to avoid such negligible loss, it would be advisable to limit the reflecting surface by a plane just below rather than through the axis N—N'. The prac- 75

tical limiting ray reflected from this part of the reflecting surface is that marked 6, and it is reflected directly out of the bulb, as are all other reflected rays from the reflecting surface of this bulb. The polar intensity diagram has been developed as in Fig. 1. The direct light accounts for the circle—part dotted—2—A—C—8, and the reflected light from the conical surface plus the direct light in this direction is shown by the dotted sloping curve D. The irregular curve marked B indicates the sum of the intensities of the direct light, and the reflected light from both the conical and the elongated bulbous portion of the reflecting surface.

Fig. 4 shows a bulb of spherical shape that is not only symmetrical about its main axis N—N', but which—except for the neck area—is symmetrical with respect to the plane perpendicular to the main axis, and shown in the drawings by the trace M—M'. A sloping dished reflector 21 is positioned in the neck and approximates a continuation of the reflecting surface of the bulb, and so completes the symmetrical relationship with respect to the plane, marked M—M'. The sloping reflector 21 extends above the main axis N—N', in order to prevent light loss in the neck, and the little bump on the polar intensity diagram, between the radii O—9 and O—1, is due to light from the upper part of this sloping reflector. Actually this part of the sloping reflector above the axis N—N' reflects the light that would normally be emitted as direct light between the radius O—2 and the axis N—N', and so lost in the neck, and reflects it as shown in the diagram, between O—7 and O—9, thus causing the bump.

It should be noted that the polar intensity diagram is symmetrical in this case, except for the small bump, discussed above. A symmetrical diagram will result from a bulb symmetrical about its main axis used in this manner, with half its surface acting as a reflector in the manner shown, provided the bulb is also symmetrical with respect to a plane perpendicular to the main axis and passing through the largest diameter of the bulb, almost without regard to the exact shape of the trace made by a plane passing through the reflecting surface and through the main axis of the bulb. Thus we do not desire to limit our invention as embodied in this type of lamp to the exact shape shown in Fig. 4, but would include within its scope all symmetrical bulbs having any reasonable shape for the trace of the surface of the general character shown as D and E in Fig. 4.

In Fig. 5 is shown a lamp in the structure of which is included a standard bulb having a silvered reflecting coating applied to its lower half and bounded by a horizontal plane through the major axis of the bulb. The filament 23 is located below the main axis of the lamp so that it is completely hooded by the reflecting surface. It is supported by lead-in wires and a supporting wire which are inclined downwardly from the mount, thus supporting the filament in its offset position. The filament itself is disposed substantially longitudinally of the bulb and maintained in a curve approximating the curvature of the wall of the bulb beneath it. The lamp is also provided with a dished reflecting disk 22 which is disposed in the neck of the bulb and in substantial continuation with its lower wall. The lead-in and supporting wires for the filament are protected by insulating tubes, similar to those shown in Fig. 2, where they pass through the re-

flecting disk 22. If desired, these may be spread so as to pass through the edges of the reflector disk rather than the center as shown in Fig. 5.

The polar intensity diagram of the lamp shown in Fig. 5 has been developed in the manner already discussed in connection with Fig. 1. Although the diagram does not show uniform intensity, and therefore indicates an asymmetrical pattern on the ceiling or wall, it will be noted that every ray striking the reflecting surfaces is reflected directly out of the bulb. In many cases this will be the preferable manner of accomplishing the desired result since the ordinary bulb, preferably of a slightly larger size than normal so as to keep the filament at the proper distance from the bulb wall, can be used, without incurring the necessary expense of making special molds to produce special shaped bulbs.

We have thus discussed a series of characteristic features which may be embodied in a bulb having a reflecting coating, and with the filament either in its normal position, or lowered or offset so as to be completely hooded by the reflecting surface, which progressively improve both the efficiency of the lighting unit and the desirability of the light pattern produced on the ceiling or other wall illuminated.

Dropping the filament below the axis of the bulb, in a lamp of this type, accomplishes another improvement in light distribution, which is equally applicable to the bulbs shown in Figs. 3 and 4. It is obvious, in all the cases illustrated, that, except for the neck area with or without the sloping reflector, the angle between the two cut-off or limiting rays in any plane through the filament center, when the filament center is located on the main axis of the lamp, is approximately 180°, and is exactly 180° for a point source of light so located. When the lamp is located in a cove, with the lamp axis and the long dimension of the cove parallel, the size of the angle between the cut-off or limiting rays in any plane passing through the axis of the lamp is not of great importance since this determines merely the amount of overlapping from adjacent lamps. However the cut-off angle in a plane perpendicular to this lamp axis is of importance, and should be preferably considerably less than 180° so that the light can be thrown farther out onto the ceiling, for example, and with greater intensity, and so that a limited amount only will fall on the side wall and so none will be lost on the side of the cove. Dropping the filament below the lamp axis actually does narrow this cut-off angle, and again makes possible a more desirable light distribution, and increased efficiency of illumination.

This cut-off angle could be narrowed by silvering more than half the area of the bulb, said area being bounded by a plane, for example, parallel to, but not through, the main axis of the lamp. However, this method would not be efficient, since much of the light striking the reflecting surface would be trapped within the reflecting surfaces, and would be reflected many times before it was finally sent out of the bulb, and therefore with a considerably reduced intensity. The same result might be attained by employing a bulb asymmetrical about its main axis, that is, it would not be a surface of revolution about the axis.

In any bulb designed for cove lighting, it is often desirable to produce a diffusing light, although since such bulbs are used largely for indirect lighting, this consideration is obviously

of less importance than when used for direct lighting. A diffusing effect can be obtained by frosting the transmitting portion of the bulb, but we prefer to accomplish this effect by employing 5 the diffusing-reflecting surfaces, disclosed in the co-pending application of Birdseye and Deren, Serial No. 47,581, filed October 31, 1935. By using these minutely roughened surfaces as highly efficient reflectors we have found that the light 10 pattern, except for the reduction of filament images and shadows, remains approximately the same as for the non-diffusing reflecting surface of the same shape. When the light is diffused by passing through a frosted surface, or when it 15 is diffused by being reflected from a reflecting surface having a relatively coarse rough surface—such as would be obtained by corrugating, for example—the light pattern itself becomes diffused, and accuracy of the reflecting surface, as 20 far as directing light in certain desired directions and with predetermined intensities in these several directions, becomes an approximation only.

Having thus described our invention, what we 25 claim as new and desire to secure by Letters Patent of the United States, is—

1. An electric lamp for cove lighting including a bulb symmetrical about the axis of the lamp having a reflecting coating applied to substantially 30 half its surface in the area bounded by a plane in which lies the axis of the lamp, and a sloping reflector position in the neck of the bulb and making an angle of less than 90 degrees with the axis of the lamp.

2. A reflecting electric lamp comprising a bulb, a filament mount located symmetrically therein and carrying a filament, the bulb having a reflecting coating applied to approximately half its surface and bounded by a plane in which lies the axis of the mount, in combination with a reflector within the bulb neck so positioned around the mount that its longest diameter makes an angle of substantially less than 90° with the axis of the mount, acting to reflect light 45 out through the non-reflecting side of the bulb.

3. A reflecting electric lamp comprising a bulb having a symmetrically located filament mount and filament therein and provided with a reflecting surface bounded by a plane in which lies the axis of the mount and including approximately 50 half the bulb area, in combination with an oval reflector located within the bulb neck about the mount and adjacent the reflecting surface of the bulb and of substantially less curvature than the adjacent portion of said reflecting surface, and forming at its adjacent portions substantially a continuation of said adjacent portions of said reflecting surface.

4. A reflecting electric lamp comprising a bulb 55 having a symmetrically located filament mount and filament therein and provided with a reflecting surface bounded by a plane in which lies the axis of the mount and including approximately half the bulb area, in combination with a dished oval reflector located within the bulb neck adjacent to the mount and contiguous to the said reflecting surface, the end portions of said neck reflector having a slope substantially the same as that of the contiguous portions of said reflecting surface, and the mid-point of said neck reflector making an angle of substantially less than 90° with the axis of the surface, whereby all 70 the light radiated from said filament is projected out of said bulb after undergoing not more than one reflection.

5. A reflecting electric lamp comprising in a single structure, a bulb, a centrally located filament, and a dished neck reflector mounted in the bulb neck at an angle with the axis of said bulb, one-half of the bulb wall being provided with a reflecting coating, all parts of which are inclined with respect to a plane perpendicular to the axis of the bulb so that all of the reflected light passes directly from the reflecting surface out through the transmitting surface of the bulb. 10

6. A reflecting electric lamp comprising a bulb which, with the exception of the neck portion thereof, is of the form of an ellipsoid of revolution, said neck portion being at one end thereof, the axis of said neck portion coinciding with the axis of revolution of said ellipse, a sloping dished neck reflector so proportioned and so placed in said neck as substantially to continue the surface of said ellipsoid of revolution through the region of said neck, and substantially to fill the cross-section of said neck, and a reflecting coating applied to approximately one-half the surface of said bulb body, said coating being bounded by the largest elliptical cross-section of said bulb. 11

7. A reflecting electric light bulb, adapted to project all the radiation of its filament, after not more than one reflection of any ray, into one hemisphere whose axis is perpendicular to the axis of the bulb, having a reflecting coating applied to one half thereof, said half being bounded by a plane in which lies the axis of said bulb, and a neck reflector mounted in the bulb neck at an angle with the axis of said bulb. 20

8. In an electric light bulb designed to project substantially all of its rays into a hemisphere whose axis is perpendicular to the axis of the bulb, a reflecting coating applied to one-half of the surface of said bulb in an area bounded by a plane in which lies the main axis of the bulb, a filament within the bulb, and a neck reflector mounted at such an angle with the axis of the bulb that rays from the filament to said neck reflector will be reflected therefrom out through the uncoated side of said bulb. 30

9. An electric lamp designed to project all of its rays into a hemisphere whose axis is perpendicular to the axis of the bulb and to produce a distribution of intensity in said hemisphere which is substantially symmetrical with respect to a plane perpendicular to the axis of said lamp through the line of maximum bulb diameter, comprising a bulb of form substantially ellipsoidal with the exception of the neck portion thereof, a reflecting coating applied to one-half the surface of said bulb in an area bounded by a plane in which lies the major axis of said ellipsoid, a dished neck reflector mounted in the neck of said bulb in a position and at an angle with said major axis effectively to produce said ellipsoidal reflecting surface past the junction line of the body of said bulb with the neck thereof, said neck reflector and said ellipsoidal reflecting surface cooperating to project all rays from a filament within said bulb in said designed manner after not more than one reflection. 40

10. A reflecting electric lamp comprising a bulb symmetrical about the axis of said lamp having a reflecting coating applied to one-half thereof and bounded by a plane in which lies the axis of said bulb, a filament located so as to intersect said plane, and a neck reflector mounted at an angle with the axis of said bulb. 50
